C. B. Desjardins
ATTORNEY.

UNITED STATES PATENT OFFICE.

EMIL A. NELSON, OF ABINGTON, PENNSYLVANIA, ASSIGNOR TO BUDD WHEEL COMPANY, OF PHILADELPHIA, PENNSYLVANIA, A CORPORATION OF THE STATE OF PENNSYLVANIA.

PROCESS OF MAKING RIMS.

Application filed February 25, 1924. Serial No. 694,894.

My invention relates to an improved process of making rims and has to do, more particularly, with a new and improved process by means of which rims for automobile 5 wheels may be manufactured.

The chief object of my invention is to provide a process of making automobile wheel rims by means of which rims can be manufactured more efficiently and at lower cost 10 than heretofore.

A further object of my invention is to provide a process of making such rims which utilizes a strip of metal of symmetrical cross section, which can be rolled conveniently at 15 the rolling mill, and which avoids the use of extensive flanging operations after the rim has been formed.

A further object of my invention is to provide a process of making rims in which the 20 cross section of the finished rim is imparted initially to the strip of metal from which the rim is to made, so as to avoid any flanging or forming operations after the strip has been welded into annular form.

25 Further objects, and objects relating to details and economies of construction and operation, will definitely appear from the detailed description to follow. In one instance, I accomplish the objects of my invention by 30 the devices and means set forth in the following specification. My invention is clearly defined and pointed out in the appended claim. A process constituting a preferred embodiment of the invention is illustrated in 35 the accompanying drawings, forming a part of this specification, in which—

Fig. 1 shows a strip of metal formed in accordance with my invention and welded to form an annulus from which two rims, are 40 to be formed, and

Fig. 2 is a similar view of a slight modification.

In the drawings, the same reference numerals refer to the same parts throughout 45 the several views.

In general, my invention consists in providing a strip of metal, which may be rolled, at the rolling mill, to a form having the cross section which is to be given to the finished 50 rims, in bending a strip of metal of this cross section, and of suitable length, to form an annulus, the adjacent ends of said strip being welded together so that a complete ring is formed, and, then, severing this annulus along

the central, longitudinal plane to form two 55 complete rims. In carrying out my invention, I provide a strip of metal having the cross-section shown in Fig. 1; and comprising the parallel body portions, 10 and 11, which lie in a single plane and are joined by 60 the semicylindrical rib, 12. At the outer edges of the portions, 10 and 11, there are provided the downwardly inclined portions, 13, from which extend the upwardly extending flanges, 14. It will be noted that this strip 65 of metal is symmetrical about the center line, and that there is a substantially equal disposition of metal above and below the plane of the portions, 10 and 11. Consequently, this is a strip or bar of a form which 70 can be produced without difficulty by the rolling mill. I take a strip of metal, of this cross section and of the desired length, depending upon the size of the rim to be formed, and bend it around into a circle so that the 75 free ends of this strip meet. These free ends are then joined together, for instance, by butt-welding, forming an annulus having the cross-section shown in Fig. 1. I next sever 80 this annulus into two similar parts by cutting along the line, 15, for instance, by circle shearing. This provides two complete rims 85 of asymmetrical form as respects their central vertical longitudinal planes, each with a side flange, formed by the two halves of the semicylindrical rib, 12, and a gutter formed by the parts, 13 and 14, which is adapted to receive a detachable side flange. By this means, I may produce two rims from 90 a single strip of metal and it will not be 95 necessary to carry out any extensive flanging or forming operations after the rim has been brought to the circular form. This makes for a more convenient and economical production of these rims, and also provides a rim which is strong and durable.

As shown in Fig. 2, I may provide a rib 16 between the portions 10 and 11, which is severed at 17, as described, and afterwards 100 subjected to a slight forming operation to bend up the portions of the rib 16 so as to form the side flanges 18, as indicated in Fig. 2 by dotted lines. This subsequent flanging operation is comparatively simple and inexpensive.

105 I am aware that the particular process described in this specification may be changed and varied considerably without departing

from the spirit of my invention and, therefore, I claim my invention broadly, as indicated by the appended claim.

Having thus described my invention, what I claim as new and useful and desire to secure by Letters Patent is—

The process of making asymmetrical rims having an upstanding fixed retaining flange on one side and a depressed gutter on the opposite side, comprising the forming of an integral metal strip with a central rib, plane portions on each side of said rib constituting the body of the rim, and gutters on the outer

edges of said plane portions whereby a symmetrical combined cross-section is devised, bending said strip into circular form, joining the ends of said strip to form an annulus, and severing said annulus along the central line of said rib to form two complete, identical and mutually independent asymmetrical rims, each adapted to retain a tire upon the seating of a detachable flange in the said gutter.

In witness whereof, I affix my signature.

EMIL A. NELSON
